United States Patent Office.

CHARLES N. HOYT, OF PROVIDENCE, RHODE ISLAND.

Letters Patent No. 91,022, dated June 8, 1869.

APPARATUS FOR PARLOR-GAMES.

The Schedule referred to in these Letters Patent and making part of the same.

To all whom it may concern:

Be it known that I, CHARLES N. HOYT, of the city and county of Providence, and State of Rhode Island, have invented a new and improved Device for Parlor-Games, &c.; and I do hereby declare that the following is a full, clear, and exact description of the same, reference being had to the accompanying drawings, making part of this specification, in which—

Figure 1 is a side elevation of my said device;

Figure 2 is a plan of the same; and

Figures 3, 4, &c., are details of its construction.

Similar letters indicate corresponding parts in all the figures.

My invention is an apparatus, consisting of one or more wheels, arranged to turn freely on a common axis, and a brake, or stop, to arrest the rotation of such wheel, or wheels, at will, to present in a given position different devices, or combinations of devices, consisting of numbers, emblems, &c., that indicate certain chances, or stages, of some entertaining game, of the character of the well-known "Mansion of Happiness," "The Royal Game of Goose," and others.

As shown in the drawings, the apparatus is designed to represent, and is a substitute for dice, for the game of "backgammon," (as the simplest illustration of its purpose,) and consists of two hexagonal wheels, A B, that turn freely on the axis, or pivot *d*, the planes, or faces *g*, of which are marked with numbers, or dots, from one to six, inclusive, and mounted in a suitable standard, F, to which is applied the brake, or stop H, consisting of a flat spring, fixed at one end in the base of the standard, and bearing against one of the faces of the said wheel, to arrest its movement, and capable of being removed from contact with the wheel, to allow

it to turn freely by an impetus given it by the hand or finger of the player.

To produce different combinations of numbers, &c., the different wheels, which may be of any desired material, are made of different weight, and with the material so distributed, or disposed in their construction, that by the same impetus the two or other number of wheels will turn with different velocities on the common axis; that is to say, one of the wheels, A, fig. 3, may be solid, and be fixed to the axis, while the other, or others, are more or less hollow, like B, fig. 3, and turn loosely on the axis, with a greater or less weight of material near the wheel's periphery, to cause it to revolve more or less rapidly, so as to insure the presentation of different combinations of numbers, or devices, with every trial, when arrested by the said brake or stop.

In carrying out my said invention, I propose to make use of wheels of larger diameter, with many faces, and to have printed, wrought, or otherwise fixed on these faces, mottoes, sentiments, emblems, devices, &c., forming distinctive features and stages of well-known or newly-devised games, for parlor and home-entertainment for young persons, for which purpose the said apparatus is peculiarly adapted.

What I claim, is—

The apparatus, as described, composed of one or more wheels, and a brake or stop, constructed for operating as and for the uses and purposes specified.

CHAS. N. HOYT.
